UNITED STATES PATENT OFFICE.

WILLIAM CAMERON, OF CHICAGO, ILLINOIS, ASSIGNOR TO TORRIS WOLD & COMPANY, OF CHICAGO, ILLINOIS, A CORPORATION OF ILLINOIS.

BEADING AND FLANGING MACHINE.

1,321,885.

Specification of Letters Patent.

Patented Nov. 18, 1919.

Application filed November 27, 1916. Serial No. 133,576.

To all whom it may concern:

Be it known that I, WILLIAM CAMERON, a citizen of the United States, residing at Chicago, in the county of Cook and State of Illinois, have invented certain new and useful Improvements in Beading and Flanging Machines, of which the following is a specification.

This invention relates to machines for making tin or sheet metal receptacles, such as lard pails and the like, which are equipped with removable covers, and has more particular reference to a machine for beading and flanging the receptacle bodies.

In the manufacture of receptacles of this character it is essential that the lower edge of the receptacle be provided with a peripheral flange to which the bottom of the receptacle is secured by a double seaming or similar operation, and it is also desirable that a bead be produced a short distance from the top of the receptacle at a point in proximity to the lower edge of the cover when the cover is applied in position on the receptacle.

One of the primary objects of my present invention is the provision of a machine which will automatically bead and flange these receptacle bodies rapidly and accurately without attention to or handling of the receptacle bodies by the operator.

Another object of my invention is to provide a machine of this character which will be simple in construction and strong and durable, and which will be capable of adjustment so that it will handle bodies of different diameters and heights.

While a machine embodying my invention is adapted to operate upon sheet metal bodies of various characters and sizes, and while these bodies are not generally, strictly speaking, called can bodies, in the sense that the word can is customarily used, nevertheless, for convenience I will hereafter refer to these bodies in this case as can bodies, using the word "can" generically to designate any sort of a cylinder body capable of being operated upon by my improved machine.

For the purpose of facilitating an understanding of my invention I have illustrated one preferred embodiment thereof on the accompanying drawings, from an inspection of which when considered in connection with

the following description my invention and its mode of operation should be readily understood. Referring to the drawings,—

Figure 1 is an elevation of a machine embodying my invention looking toward the delivery end thereof;

Fig. 2 is a side elevation looking toward the left in Fig. 1, certain parts being broken away to more clearly illustrate certain features;

Fig. 3 is a sectional view taken on the line 3—3 of Fig. 1;

Fig. 4 is an enlarged sectional view on the line 4—4 of Fig. 3;

Fig. 5 is a detail sectional view on the line 5—5 of Fig. 3;

Fig. 6 is a sectional view on the line 6—6 of Fig. 2; and

Fig. 7 is a fragmentary plan view, viewed from the line 7—7 of Fig. 2.

By reference to the drawings it will be observed that the machine comprises a body or frame construction, designated generally by reference character 8, which is designed and proportioned to accommodate and carry the various mechanisms to be hereinafter described. A shaft 9, hereinafter referred to as the cam shaft, is journaled in suitable bearings and extends transversely of the machine, one end of the shaft being equipped with a loosely mounted belt pulley 11 adapted to be secured to the shaft at will by the manipulation of a clutch member 12 splined on the shaft and constructed to engage with a companion clutch member 13 carried by the pulley 11. The pulley 11 constitutes the drive pulley for the machine and power is applied to this pulley from any suitable source through an ordinary belt.

Above the shaft 9 there is mounted in suitable journal bearings 14 and 15 a chuck shaft 16 carrying at its inner end a chuck 17. This shaft also has fixed thereon between the bearings 14 and 15 a belt pulley 18 and a grooved collar 19, into the groove of which projects a pair of rollers or studs 21 carried by the bifurcated upper end of a lever 22 fulcrumed on the main frame at 23. A contractile spring 24 fixed at one end to the frame of the machine and at its other to an arm 25 projecting from the lever 22, normally urges the upper end of the lever outwardly into the position shown in Fig. 1,

but at periodic intervals the lever is swung so as to move its upper end inwardly by means of a cam 26 mounted upon the shaft 9, the lower end of the lever 22 being 5 equipped with a roller 27 riding upon the face of the cam 26.

A similar chuck shaft 28 is mounted in the bearings 29 and 31 in axial alinement with the shaft 16. This shaft carries at its inner 10 end a chuck 32 opposed to the chuck 17 and is also equipped with a belt pulley 33 and a grooved collar 34, and the shaft is reciprocated longitudinally by a lever 35, which is moved in one direction by a cam 36 mounted 15 on the shaft 9 and in the other direction by a spring 37, all similar in construction and operation to the mechanism on the other side of the machine, which has been previously described. The cams 26 and 36 are so 20 designed and mounted that the two shafts 16 and 28 will be moved synchronously to cause the chucks 17 and 32 to approach each other and recede away from each other at regular predetermined intervals.

25 Referring now to Fig. 2, it will be observed that the feeding or receiving end of the machine is provided with an inclined chute 38. This chute comprises two side members and a bottom member of suitable 30 construction, the side members being carried by blocks 39 and 41, adjustably mounted in supporting guideways, 42 and 43 respectively, carried by a frame structure including a casting 44 which is vertically adjustable in a guideway 45 fixed to the main frame of the machine. The lateral adjustability of the side members of the chute enables the chute to be accommodated to can bodies of various heights or lengths, 35 which are fed to the receiving end of the chute manually, or otherwise, and are permitted to roll down the chute to the lower end thereof, a number of can bodies being shown in dotted lines in Figs. 2 and 3 and 40 indicated by reference character 46.

Near the lower end of the chute there is 45 mounted a transferrer, which is designed to transfer the foremost can from the chute into position between the retracted chucks 50 17 and 32 and in substantially axial alinement with these chucks. This transferrer consists of a pair of members 47 having flat upper faces adapted when in lowered position to form a continuation of the bottom 55 of the chute 38, the upper ends of these members being curved upwardly as indicated at 48 to serve as a stop or abutment for the foremost can-body, the rear ends of the members being provided with a downwardly 60 extending arm or finger 49 which, as the transfer members are swung upwardly to transfer a can-body, serve to hold back the following can-bodies in the chute as shown in Fig. 3. Each of the members 47 65 is mounted upon a block 51 by a slot and

bolt connection so as to be laterally adjustable toward and from each other to accommodate them to can-bodies of various lengths. The blocks 51 are mounted upon a pair of arms 52 pivoted at their rear ends 70 upon a shaft 53 supported intermediate its ends in a block 54 mounted upon a bracket 55 carried by the machine frame, as best shown in Figs. 2, 3 and 6. A link 56 disposed between the arms 52 is bifurcated at its lower end to straddle the shaft 9 and carries at one side an anti-friction roller 57 which travels upon a cam 58 mounted upon the shaft 9, suitable contractile springs 59 being employed to maintain 75 the roller 57 against the cam face. The upper end of the link 56 is adjustably connected to both of the arms 52 by means of a bolt 61 which extends through the link and through elongated slots 63 formed in the 80 arms 52 so that by varying the position of the bolt in these slots the extent of movement of the arms, and thereby the travel of the transerrer members 47, at each revolution of the shaft 9 may be regulated and adjusted. 85

When the parts are in the position shown in Fig. 2 the foremost can-body will rest upon the transerrer members 47, and as the shaft 9 revolves into the position shown 90 in Fig. 3 the transerrer members will be swung upwardly to carry the foremost can-body into position between the chucks 17 and 32. The fingers 49 during this movement prevent the succeeding can-bodies from 95 rolling down the chute and the cams 26 and 36 are so timed that when the can-body has been alined with the chucks both chucks 100 will be moved inwardly toward each other into the opposite ends of the can-body. 105

To assist in alining the can-body with the chucks I have provided a guide-member 110 64 which overlies the chute and prevents the can-bodies from becoming displaced, the rear end of this guide-member being provided with a resilient extension 65 which tends to hold the can-body down upon the transerrer members 47, as it is moved into position. A pair of cheek pieces or side plates 66 and 67 are carried upon angle 115 members, 68 and 69 respectively, which are supported upon blocks 71 mounted for lateral adjustment in a guiding support 72 having a downward extension 73 which is vertically adjustable upon the rear face of 120 the block 54. The blocks 71, carrying with them the angle pieces 68 and 69, upon which the side plates 66 and 67 are mounted, are capable of lateral adjustment to accommodate various lengths of cans, and are normally adjusted so that the can-bodies will 125 enter between the side plates with only comparatively slight clearance. The side plates are also provided with openings through which the chucks 17 and 32 may be pro- 130

jected into the can body, as shown in Fig. 4. To further assist in alining and positioning the can-body for the reception of the chucks, each side plate has mounted upon its inner face a roller 74 carried by a bar 75 which is adjustable upon the side plate by reason of an elongated slot 70 in the side plate, through which the securing screw 80 projects. These rollers 74 serve as abutments against which the can-body is moved by the transferrer members, and upon rotation of the can-body by the chucks these rollers hold the body snugly against the chucks and prevent the ends of the body from becoming distorted.

It will be understood that the chucks are continuously rotated at an appropriate speed by means of belts which are trained over the pulleys 18 and 33, and when a can-body has been positioned in alinement with the chucks they are moved inwardly into the body as shown in Fig. 4, whereupon the body is revolved with the chucks. The chuck 32 is provided with an inclined face 76 and chuck 17 is provided with a groove 77 and a bead 78, all as shown in Fig. 4. Furthermore, the chuck 17 is provided outside the bead 78 with a cylindrical portion 79 so that the upper end of the can body, when conformed to this portion 79, is cylindrical so as to receive the cover while the portion of the body below the bead is generally tapered toward the bottom as is customary in pails of this character, and as shown in Fig. 4. While the can is revolving with the chucks a flanging roller 81 and a beading roller 82 are forced against the outer face of the can into coöperative relation with the chucks to produce a flange at the lower end of the can-body and a bead near the upper end, as will be evident from Fig. 4. It will be understood that the roller 81 is provided with an inclined face 83 coöperating with the face 76 of the chuck 32 while the roller 82 is provided with a bead 84 and a groove 85 coöperating with the groove and bead respectively on the chuck 17. The rollers 81 and 82 are carried by blocks 86 which are laterally adjustable upon a crosshead 87, the blocks being secured thereto by bolts 88 passed through elongated slots 89 in the crosshead. This crosshead is pivotally mounted upon a shaft 91 carried by suitable bearings 92 formed on the main frame of the machine and is provided with a rearwardly extending arm 93 to which there is adjustably connected a link 94. The lower end of this link is bifurcated to straddle the shaft 9, as shown in Fig. 3, and upon one side of the link there is mounted an anti-friction roller 95 bearing upon the periphery of a cam 96 mounted upon the shaft 9, the roller being urged against the cam face by a contractile spring 97. The cam 96 is so timed that when the chucks have entered the can-body

so that the body is rotating with the chucks, the crosshead will be swung on its shaft 91 to force the flanging and beading rollers, 81 and 82 respectively, against the can-body so that in conjunction with the chucks the required operations are simultaneously performed upon the body. After a sufficient number of revolutions of the body have occurred to complete the operation, the beading and flanging rollers are withdrawn from the chucks and the chucks are then drawn apart, permitting the body to drop down upon the angle members 68 and 69 and roll to the lower ends of these members, where they are discharged from the machine into any suitable receptacle. Side plates 98 are preferably mounted upon the angle members 68 and 69 to insure the travel of the can-bodies to the lower end of the delivery chute and prevent any possibility of their being dropped into the machinery.

It should be obvious, from the foregoing, that the can-bodies fed into the receiving chute roll down to the transferrer by which they are transferred one at a time and accurately positioned between the chucks, whereupon the chucks are moved toward each other into the ends of the body, thus causing the body to revolve with the chucks. The abutment rollers 74 assist in alining the body with the chucks and also prevent distortion of the body while it is being revolved by the chucks. During the revolution of the body the beading and flanging rollers are forced into coöperative relation with the chucks to produce the required bead and flange. After the operation is complete the rollers are withdrawn and the chucks are retracted, thus permitting the beaded and flanged body to drop into the delivery chute and be discharged from the machine. In the meantime the transferrer has returned to lowered position to receive the next succeeding can-body which is then positioned at the proper time between the chucks, whereupon the operation is repeated.

It is believed that my invention and its mode of operation should be understood from the foregoing without further description and it should be manifest that the structural details of the machine disclosed are capable of considerable modification and variation within the scope of the appended claims.

I claim:

1. In a can making machine, the combination with rotatable can holding chucks and a tool in coöperative relation thereto, of a feed table having its discharge end below the chucks, and an oscillating transferrer working between the discharge end of the feed table and the chucks, said transferrer including spaced rails constituting continuations of the feed table in the receiving position of the transferrer, said rails being ad-

130

justable with respect to one another to accommodate the transferrer to cans of different lengths, upstanding stops at the discharge ends of the rails to prevent escape of 5 the cans in the receiving position of the transferrer, and the rear ends of the rails being provided with depending stops lying across the discharge end of the feed table in the discharging position of the transferrer 10 to prevent the escape of cans from the feed table.

2. In a can making machine, the combination of rotatable can holding chucks and a tool in coöperative relation thereto, of a feed 15 table having its discharge end below the chucks, an oscillating transferrer working between the discharge end of the feed table and the chucks, and means for insuring the alinement of a can body with the chucks including a pair of adjustable abutment rollers for engagement by a can transferred to the chucks by the transferrer.

3. In a can making machine, the combination with rotatable can holding chucks and 25 a tool in coöperative relation thereto, of a feed table having its end below the chucks, an oscillating can transferrer working between the discharge end of the feed table and the chucks, a pair of adjustable abutment rollers in position to aline a can body 30 with the chucks, and an elastically yieldable guide member disposed above and in the path of a can being transferred from the feed table to the chucks.

35 4. In a can making machine, the combination with rotatable can holding chucks and a tool in coöperative relation thereto, of a pair of side plates having openings in alinement with the respective chucks, means for 40 moving the chucks toward and away from one another through said openings, a feed table, a can transferrer working between the feed table and the chucks, and can alining means adjustably carried by the side plates.

45 5. In a beading and flanging machine, the combination of a pair of longitudinally movable rotatable chucks, a chute, oscillatory means for transferring a can body from said chute to said chucks, means for insuring the alinement of the can body with said chucks, said means including a pair of adjustable abutment rollers and a resilient 50 guide member, and means coöperating with

said chucks to bead and flange said positioned body.

55

6. In a beading and flanging machine, the combination of a pair of chucks adapted to loosely fit within the ends of a can body, a chute, a pair of pivotally mounted arms, a member adjustably carried upon each arm, means for oscillating said arms to transfer a can body from said chute to said chucks, said members being provided with downwardly extending fingers for holding the remaining bodies in the chute during the transfer of the foremost body, means coöperating with said transfer members to accurately position said body with respect to the chucks, means for moving said chucks into engagement with the ends of said body whereby 70 said body is rotated, and means rotatable by frictional engagement with said rotated body for beading and flanging said body.

65

7. In a beading and flanging machine, the combination of a pair of rotatable and longitudinally reciprocable chucks, a beading roller, a flanging roller, a head upon which said rollers are adjustably mounted so as to be capable of adjustment toward and from each other, means for operating said head 80 to bring the rollers into coöperative relation with said chucks, a chute, a transferrer, and a plurality of work alining devices mounted in proximity to said chucks, said chute, transferrer and work alining devices being adjustable to accommodate can-bodies of various sizes.

75

8. In a can making machine, the combination of rotatable and longitudinally reciprocable chucks, a feed table having its discharge end below the chucks, an oscillating transferrer working between the discharge end of the feed table and the chucks and provided with a stop extending across the discharge end of the feed table in the discharging position of the transferrer, an oscillating cross-head mounted above the feed table, spaced tools adjustably carried by the cross-head and in coöperative relation to the chucks, a can alining means in coöperative 90 relation to the chucks, an elastically yieldable can guide disposed above the discharge end of the feed table and in the path of a can being transferred from the feed table to the chucks.
